UNITED STATES PATENT OFFICE.

RICHARD LESTER WILCOX AND ZENAS P. CANDEE, OF WATERBURY, CONNECTICUT,
ASSIGNORS TO THE WATERBURY FARREL FOUNDRY AND MACHINE COMPANY, OF
WATERBURY, CONNECTICUT, A CORPORATION OF CONNECTICUT.

METHOD OF MAKING BULLETS OR OTHER ARTICLES OF MANUFACTURE.

1,149,485.

Specification of Letters Patent. Patented Aug. 10, 1915.

Application filed January 25, 1915. Serial No. 4,151.

To all whom it may concern:

Be it known that we, RICHARD LESTER WILCOX and ZENAS P. CANDEE, citizens of the United States, residing at Waterbury, in the county of New Haven and State of Connecticut, have invented certain new and useful Improvements in Methods of Making Bullets or other Articles of Manufacture, of which the following is a specification, reference being had therein to the accompanying drawings.

Our invention relates to a new and improved method of making bullets, or other articles of manufacture, and has for its object, among other things, the production of said bullets or such articles by a process that will produce them in quantities at the minimum cost and of uniform size and shape with the opposite ends thereof concentric with each other.

To these, and other ends, our invention consists in the improved method of making bullets, or other articles of manufacture, substantially as hereinafter described and more particularly pointed out in the claims.

Referring to the drawings, in which like numerals of reference designate like parts in the several figures, Figure 1 is a side elevation of a portion of a cylindrical rod, from which the article is produced; Figs. 2, 3, and 4 illustrate the successive operations; Fig. 5 illustrates a completed bullet; and Fig. 6 a sectional view of an incomplete bullet, taken upon line 6—6 of Fig. 2.

The bullet illustrated in the drawings has its greatest diameter between its ends and tapers toward each end, with an annular groove around the outside thereof. Our invention will be described as applied to this general form of bullet, but we desire it understood, however, that it is not limited thereto, but may be utilized to produce other forms of bullets as well as articles of manufacture for other uses. Heretofore it has been difficult to make bullets of this character that will be accurate in form and shape, of uniform dimensions, and with the opposite ends thereof concentric with each other. The result has been that these bullets have heretofore only been produced with fine tools operated by skilled workmen at a high cost and with a small output. To overcome these, and other objections, we have devised a method for producing these

bullets rapidly, at a very low cost, and with 55 labor of ordinary skill operating tools that are more or less in common use. The bullets so manufactured are all of absolutely uniform size and shape. In brief, we produce by this method a better bullet in very much 60 larger relative quantities and at a much lower cost.

In the practice of our invention we make the bullet from a wire rod taken from a coil of wire, and in Fig. 1 is illustrated a 65 fragmentary portion of such wire rod.

The blank or wire rod from which the bullet is made is first pinched at the point between dies in a power press or similar device. This produces a blank substantially the same as that shown in Fig. 2, a fin being formed around the edge thereof at the point where the dies meet. This fin is next removed by putting the blank into either a pointing machine or a trimming 70 machine, whichever may be preferred, and the result is the blank shown in Fig. 3.

The blank may be cut off from the wire rod either before or after the operations illustrated in Figs. 2 and 3, but we prefer 75 that this be done after the operation set forth in Fig. 2 has been completed, although this is not material. After the blank has been trimmed it is placed in a heading machine and the rear end thereof 80 swaged into its finished shape, which operation creates a fin 2 around the outside thereof, which is subsequently turned off and the bullet is completed.

If it is desired to cut a groove in the 85 bullet, such as illustrated by the numeral 3, in Fig. 5, it is formed at the same time that the fin 2 is removed.

Ordinarily these bullets have been made upon a screw machine, the pointed end being first turned and the blank then cut off from the rod after which the opposite end has been turned. With this process it is practically impossible to produce bullets of absolutely uniform diameter, and as the 90 rear end of the bullet is sized, shaped and turned by holding the pointed end in a clutch or similar device, it is rarely ever concentric with the pointed end, and frequently the pointed end is marred and 95 roughened by the clutch jaws; and again, the metal of which the bullets are frequently made is of such character that it cannot be 100 105

turned and leave a smooth surface. If the opposite ends of the bullet are not concentric with each other, the bullet is useless, as its direction of flight and trajectory are not true, so much so as to prevent accurate firing.

With our process the bullet is formed without turning the outside thereof and it can be properly sized and shaped irrespective of the character of the metal of which the bullet is made. By arrangement of the swaging mechanism, which does not rotate, the fin 2 is always formed at the point where the groove is to be made, so that it may be taken off while making the groove.

In the drawings we have illustrated a bullet with a slightly flattened nose, this being the usual requirement, but by our method the nose can be brought to a pin point if necessary, the shape of the pinching dies being slightly modified to produce this result.

Having described our invention, what we claim as new and desire to secure by Letters Patent, is:—

1. The method of making an article of

manufacture, comprising the pinching of the end of a rod so as to point the same, removing the fin formed thereby, cutting a length from the rod from which the article is made, swaging the end of said article opposite the pointed end and removing the fin formed by said swaging operation.

2. The method of making an article of manufacture having an annular groove around the outside thereof, comprising, the pinching of the end of a rod so as to point the same, removing the fin formed thereby, cutting a length from the rod from which the article is made, swaging the end of said article opposite the pointed end so as to form the fin resulting from this operation at the point where the groove is to be, and removing this latter fin and cutting said groove at one and the same time.

In testimony whereof we affix our signatures in presence of two witnesses.

RICHARD LESTER WILCOX.
ZENAS P. CANDEE.
